UNITED STATES PATENT OFFICE.

HERBERT J. SASS AND OLIVER H. SHAW, OF CHICAGO, ILLINOIS.

SPARKING INDICATOR.

1,210,214.

Specification of Letters Patent. Patented Dec. 26, 1916.

Application filed February 29, 1916. Serial No. 81,111.

To all whom it may concern:

Be it known that we, HERBERT J. SASS and OLIVER H. SHAW, residents of Norwood Park, Chicago, county of Cook, and State of Illinois, have invented certain new and useful Improvements in Sparking Indicators, of which the following is a specification.

Our invention relates to sparking indicators that is devices designed for use in connection with a multiple cylinder internal combustion engine for ascertaining whether or not the spark plugs of the engine are sparking during operation of the engine.

The object of our invention is the production of an indicator as mentioned which will be of simple and economical construction and through the medium of which the spark plugs of an engine may be readily and quickly tested to determine whether or not the same are operating.

Other objects will appear hereinafter.

The invention consists in the combinations and arrangements of parts hereinafter described and claimed.

The invention will be best understood by reference to the accompanying drawings forming a part of this specification, and in which—

Figure 1 is a partially diagrammatic plan view of an indicator embodying the invention and connected up for coöperation with the spark plugs and magneto of a conventional automobile engine, Fig. 2 is a front elevation of the device, Fig. 3 is a front elevation of the device with the cover plate removed, and Figs. 4 and 5 are enlarged sections taken on lines 4—4 and 5—5 respectively of Fig. 3.

The preferred form of construction as illustrated in the drawings comprises a stationary holder or rectangular block 6 of insulating material. To the member 6 are secured side pieces 7 and 8 and end pieces 9 and 10 of insulating material.

The stationary holder 6 carries platinum sparking points 11 which are provided at the inner ends of binding posts 12 which are threaded in said holder. Lock nuts 13 cooperate with the binding posts 12 to lock the same in position. Additional nuts 14 are provided for fastening the conductor wires to said posts.

Formed in the front side of member 6 is an elongated channel 15 in which is slidably mounted an elongated movable holder 16 of insulating material. The member 16 is held

in position in channel 15 by means of a cover plate 17 which is also of insulating material. Carried by the holder 16 are laterally projecting arms 18 of conductive material which are countersunk in said holder and which are provided at their outer ends with platinum sparking points 19 adapted for coöperation with the sparking points 11 in the formation of sparking gaps as will be readily understood. The arrangement is such as will be seen that the sparking points 19 may be moved toward and from the points 11 in order to increase or decrease the width of the gaps formed between said sparking points by simply shifting the holder 16 in channel 15.

The arms 18 are secured to the member 16 by means of rivets or other suitable fastening devices 20 which pass through said holder, said members 20 being provided at their inner ends with elongated heads or plates 21 which constitute contact members. Mounted in the stationary holder 16 are binding posts 22 locked in position by lock nuts 23, additional nuts 24 being provided for securing of the conducting wires thereto. A constant electrical connection between the binding posts 22 and the contact plates 21 is established by means of brushes 25 of carbon or other conductive material which are held in constant engagement with said plates 21 by means of helical compression springs 26 which are interposed between the brushes 25 and the heads or inner ends of binding posts 22, said springs serving also as a means of electrical connection between said brushes and posts.

Sliding adjustment of movable holder 16 is effected by means of a screw 27 which is threaded in the end member 10, the inner end of said screw 27 being in swiveled connection with the corresponding end of said holder. A knurled exteriorly positioned head 28 affords means for readily manually rotating said screw in order to secure the desired adjustment of the member 16 and hence of the movable sparking points 19 carried thereby. Formed in the cover plate 17 are spaced exposure openings 29 through which the sparking gaps may be viewed as will be readily understood.

In using the device the same is preferably mounted upon the dashboard of the automobile, laterally projecting ears 30 being provided for this purpose. The binding posts 12 are connected with the magneto of the

automobile engine and the binding posts 22 are connected with the spark plugs of the engine. With this arrangement it will be seen that the device is in series with the magneto and spark plugs so that when it is desired to test the spark plugs it is only necessary to adjust the screw 27 to move the sparking points 19 from the sparking points 11.

10 It is of course understood that the jumping of a spark between corresponding points 11 and 19 indicates that the spark plug with which the same co-operates is also operating, the absence of a spark as mentioned serving 15 to indicate that the corresponding spark plug of the engine is fouling. Thus it will be seen that the spark plugs may be readily and easily tested by the operator of the automobile from a position in the driver's seat of 20 the vehicle.

The device also serves as a means of cleaning the spark plugs, it having been found that when the sparking points are adjusted to form a comparatively wide gap between 25 the corresponding spark points, the charge accumulates in order to force a spark across the gap, thus resulting in considerable disturbance at the sparking points in the spark plug which in many instances will remove 30 any foreign matter which may be coating the same.

While we have illustrated and described the preferred form of construction for carrying our invention into effect this is capable 35 of variation and modification without departing from the spirit of this invention. We, therefore, do not wish to be limited to the precise details of construction set forth, but desire to avail ourselves of such variations and modifications as come within the 40 scope of the appended claims.

Having described our invention what we claim as new and desire to secure by Letters Patent is:

45 1. A sparking indicator comprising, in combination, a stationary holder of insulating material; a channel provided in one side of said stationary holder; a movable holder of insulating material adjustably mounted 50 in said channel; a plurality of sparking points carried by the stationary holder; a plurality of sparking points carried by the movable holder adapted to be carried toward and from said first mentioned sparking 55 points by movement of said movable holder; and means for moving said movable holder, substantially as described.

60 2. A sparking indicator comprising, in combination, a stationary holder of insulating material; a channel provided in one side of said stationary holder; a movable holder of insulating material adjustably mounted 65 in said channel; a plurality of sparking points carried by the stationary holder; a plurality of sparking points carried by the stationary holder;

movable holder adapted to be carried toward and from said first mentioned sparking points by movement of said movable holder; and a manually adjustable screw co-operating with said movable holder for adjusting 70 the same, substantially as described.

3. A sparking indicator comprising, in combination, a stationary holder of insulating material; a channel provided in one side of said stationary holder; a movable holder of insulating material adjustably mounted 75 in said channel; a plurality of sparking points carried by the stationary holder; a plurality of sparking points carried by the movable holder adapted to be carried toward and from said first mentioned sparking points by movement of said movable holder; a manually adjustable screw co-operating with said movable holder for adjusting 80 the same; binding posts on said stationary holder; and spring pressed brushes for connecting said binding posts with the sparking points of said movable holder, substantially as described.

4. A sparking indicator comprising, in combination, a stationary holder of insulating material; a channel provided in one side of said stationary holder; a movable holder of insulating material adjustably mounted 90 in said channel; a plurality of sparking points carried by the stationary holder; a plurality of sparking points carried by the movable holder adapted to be carried toward and from said first mentioned sparking points by movement of said movable 95 holder; means for moving said movable holder; binding posts on said stationary holder; means electrically connecting said binding posts with the sparking points of said movable holder, said means comprising 100 elongated contact plates at the under side of said movable holder electrically connected with the sparking points thereof; and spring pressed brushes mounted in said stationary holder adapted to constantly engage with said plates and electrically connect the same with said binding posts, substantially as described.

5. A sparking indicator comprising, in combination, a stationary holder of insulating material; a movable holder of insulating material adjustably mounted on said stationary holder; a plurality of sparking points carried by the stationary holder; a plurality of sparking points carried by the movable holder adapted to be carried toward and from said first mentioned sparking points by movement of said movable holder; means for moving said movable holder; and a cover plate arranged over said 115 120 125 130

sparking points having spaced openings through which said sparking points may be viewed, substantially as described.

6. A sparking indicator comprising, in combination, a stationary holder of insulat-

ing material; a channel provided in one side of said stationary holder; a movable holder of insulating material slidably mounted in said channel; a plurality of sparking points 5 carried by the stationary holder; binding posts electrically connected with said sparking points; a plurality of spaced arms of conductive material carried by and laterally projecting from said movable holder; sparking points on the outer ends of said arms adapted to be moved toward and from said first mentioned sparking points by movement of said movable holder; binding posts in said stationary holder in constant electrical connection with said arms; and manually operable means for moving said movable holder, substantially as described.

7. A sparking indicator comprising, in combination, a stationary holder of insulating material; a channel provided in one side of said stationary holder; a movable holder of insulating material slidably mounted in said channel; a plurality of sparking points 20

carried by the stationary holder; binding posts electrically connected with said sparking points; a plurality of spaced arms of conductive material carried by and laterally projecting from said movable holder; sparking points on the outer ends of said arms adapted to be moved toward and from said first mentioned sparking points by movement of said movable holder; binding posts in said stationary holder in constant electrical connection with said arms; and an exteriorly projecting screw having one end in 25 swiveled connection with said movable holder for adjusting the latter, substantially as described.

In testimony whereof we have signed our names to this specification in the presence 30 of two subscribing witnesses.
